(57) **CLAIM**

The ornamental design for an earphone component, as shown and described.

DESCRIPTION

Figure 1.1 is a perspective view of one earphone component.

Figure 1.2 is a front side elevation view of Figure 1.1

Figure 1.3 is a back side elevation view of Figure 1.1

Figure 1.4 is a left side elevation view of Figure 1.1

Figure 1.5 is a right side elevation view of Figure 1.1

Figure 1.6 is a top side plan view of Figure 1.1

Figure 1.7 is a bottom side plan view of Figure 1.1

Figure 1.8 is a reference view of the earphone component as configured for use.

Figure 4.1 is a front side elevation view of one earphone component

Figure 4.2 is a back side elevation view of Figure 4.1

Figure 4.3 is left side elevation view of Figure 4.1

Figure 4.4 is a right side elevation view of Figure 4.1

Figure 4.5 is a top side plan view of Figure 4.1

Figure 4.6 is a bottom view of Figure 4.1

Figure 4.7 is a perspective view of Figure 4.1

Figure 4.8 is a reference view of the earphone component as configured for use.

(Continued)

The faded areas in Figures **1.8**, **1.9** and **4.8** are reference views thereof and show environmental matter showing the designs in use, and form no part of the claimed designs.
